UNITED STATES PATENT OFFICE

106,883

DESIGN FOR A DISPENSER FOR LUBRICANTS OR THE LIKE

Charles W. Ginter, Bryan, Ohio, assignor to The Aro Equipment Corporation, Bryan, Ohio, a corporation of Ohio

Application August 9, 1937, Serial No. 70,940

Term of patent 7 years

To all whom it may concern:

Be it known that I, Charles W. Ginter, a citizen of the United States and a resident of Bryan, in the county of Williams and State of Ohio, have invented a new, original, and ornamental Design for a Dispenser for Lubricants or the like, of which the following is a specification, reference being had to the accompanying drawings, forming part thereof.

Figure 1 is a top plan view of a dispenser for lubricants or the like showing my new design.

Figure 2 is a side elevational view thereof.
Figure 3 is an end elevational view thereof;
and

Figure 4 is a perspective view of my dispenser.

I claim:

The ornamental design for a dispenser for lubricants or the like substantially as shown.

CHARLES W. GINTER.
